UNITED STATES PATENT OFFICE

2,446,735

LOCK-BOLT OPERATED DOOR FASTENER

William Francis Banham, London, England

Application April 29, 1947, Serial No. 744,544
In Great Britain March 26, 1946

Section 1, Public Law 690, August 8, 1946

3 Claims. (Cl. 292—33)

1

This invention relates to improvements in locks or door fastenings of the type comprising a plurality of independent bolts mounted in the door jamb which are shot upon operation of the normal bolt or spring latch of the door; the independent bolts engaging the door and preventing the opening thereof until the normal bolt or spring latch is withdrawn.

The present invention is concerned more especially with a door fastening for use with locks of the Yale type, the latching of which is intended to effect the automatic operation of secondary bolts mounted in the jamb of the door.

According to the invention there is provided at least two mortice bolts fitted within the jamb of a door and interconnected by an axially rotatable rod carrying an abutment member movable by the latch of the door lock to force said mortice bolts into engagement with the door, resilient means being provided to return said mortice bolts to the inoperative position when the door latch is withdrawn to open the door.

Preferably, the mortice bolts are fitted adjacent the top and bottom of the door jamb so that when in the locking position they engage the edge of the door near the top and bottom and prevent it being opened when the normal door latch is engaged. The mortice bolts are spring loaded so that they are automatically returned to the unlocked position or the interconnecting rod carrying the abutment may have a coiled spring mounted thereon which is placed under tension when the rod is actuated through the abutment thereon and serves to return the mortice bolts by means of levers fixed to the operating rod.

In order that the invention may be clearly understood and readily carried into effect, reference is directed to the accompanying drawings, wherein:

Fig. 1 is a front elevation partly in section of a door jamb fitted with a door fastening in accordance with the invention and showing a door partly closed to the jamb.

Fig. 2 is a similar view to Fig. 1 with the door completely closed.

Fig. 3 is a section on the line 3—3, Fig. 1.

Fig. 4 is a longitudinal section of the mortice bolt housing, and

Fig. 5 is a side elevation of the mortice bolt, and

Fig. 6 is an end view of Fig. 5, and

Fig. 7 is a plan of Fig. 4.

Fig. 8 is a plan of Fig. 5.

Fig. 9 is an end view of Fig. 8.

2

Referring to the drawings which illustrate a preferred construction according to the invention, 10 indicates a door and 11 a door jamb, two mortice bolts 12, 12, being fitted within the jamb 11 to co-operate with locking recesses 13, 13, provided in the door 10. Preferably, the mortice bolts are fitted adjacent the top and bottom of the door jamb so that when in the locking position they engage the edge of the door 10 at the top and bottom and prevent it being opened when the normal door latch is in the engaged position. The mortice bolts are interconnected and simultaneously actuated by an axially rotatable rod 14 carrying an abutment member in the form of a plate 15 movable by the spring latch 16 of the normal door lock 17 to move the rod 14 about its axis. The extremities of the rod engage the mortice bolts through the intermediary of levers 18 serving to move said mortice bolts 12, 12, into locking engagement with the recesses 13, 13, when the spring latch 16 is engaged with the box staple 19 of the door lock 17. The mortice bolts are spring loaded for automatic return by hair pin springs 20 when the spring latch 16 is withdrawn from the box staple 19.

The three locks i. e. the two mortice bolts and the spring latch operate simultaneously when the tongue of the spring lock is shot into its box staple on the closing of the door, or in the case of a dead lock by the turn of the key.

The mortice bolts 12, 12, are each fitted in a housing 21 which is secured within the jamb of the door by means of a base plate 22. The housing is a rectangular tubular cross-section within which the mortice bolt 12 is slidably fitted, the housing being provided with an inwardly projecting pin 23 which engages a groove 24 in the mortice bolt and in conjunction with a pin 25 fixed within the groove, limits the relative movement between the mortice bolt and the housing. In addition, the mortice bolt 12 is provided with a projecting pin 26 which engages a channel 27 formed in the side wall of the housing 21 and closed at the outer end as at 28. The closed end 28 in conjunction with the pin 26 limits the movement of the mortice bolt in the outward or locking direction. A recess 29 is formed in that side of the mortice bolt opposite to the side carrying the pin 26 to form an abutment for one end of the hair pin spring 20 which bears against the rear edge of the recess 29 and normally maintains the mortice bolt in the retracted position, as shown in Fig. 3. The hair pin spring 20 is suitably mounted in the jamb of

the door. The mortice bolt 12 is moved to the outward or locking position upon operation of the axially rotatable rod 14 by the levers 18, 18. Each lever 18 is of arcuate form and integral with the rod 14, the free extremity of the lever bearing against the face 30 of the recess 29 to move the mortice bolt 12 against the pressure of the spring 20. The ends of the axially rotatable rod 14 fit conveniently a pair of bearings 31 which form part of the mortice bolt housing 21.

In place of the hair pin springs 30, the axially rotatable rod 14 may be provided with a coil spring 32 which is secured thereto at one end and anchored at the other end in the slot 33 provided in the door jamb for the reception of the rod 14. A slot 34 in the housing and coincident with the recess 29 permits the lever 18 to enter the housing and contact the mortice bolt.

What I claim and desire to secure by Letters Patent is:

1. A lock or door fastening of the kind described having at least two mortice bolts fitted within the jamb of a door and interconnected by an axially rotatable rod carrying an abutment member movable by the latch of the door lock to force said mortice bolts into engagement with the door, resilient means being provided to re-

turn said mortice bolts to the inoperative position when the door latch is withdrawn to open the door.

2. A lock or door fastening as claimed in claim 1, wherein the axially rotatable rod carries levers operatively associated with the mortice bolts to move them to the locking position, the mortice bolts being spring loaded for return to the inoperative position.

3. A lock or door fastening as claimed in claim 1, wherein the mortice bolts are mounted in a tubular housing of rectangular cross-section secured to the door jamb, means being provided to limit the relative movement between the mortice bolts and their housing.

WILLIAM FRANCIS BANHAM.
